(57) **CLAIM**

The ornamental design for an electronic device with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device having a display screen with animated graphical user interface showing a first image of the claimed design;

FIG. 2 is a second image thereof;

FIG. 3 is a third image thereof;

FIG. 4 fourth image thereof;

FIG. 5 is a fifth image thereof;

FIG. 6 is a sixth image thereof;

FIG. 7 is a front view of another embodiment thereof showing a first image of the claimed design;

FIG. 8 is a second image thereof;

FIG. 9 is third image thereof;

FIG. 10 is a fourth image thereof;

FIG. 11 is a fifth image thereof;

FIG. 12 is a sixth image thereof; and,

FIG. 13 is a front view of an electronic device having a display screen with the animated graphical user interface of FIG. 1 applied to the display screen. The animated graphical user interface designs of FIGS. 2-12 may be similarly applied thereto.

The broken lines in the figures show a display screen or portion thereof, or an electronic device having a display screen, and form no part of the claimed design.

The appearance of the animated image sequentially transitions between the images shown in FIGS. 1-6, and FIGS. 7-12, respectively. The process or period in which one image transitions to another forms no part of the claimed design.
